UNITED STATES PATENT OFFICE

OSCAR T. THOMPSON, OF NEENAH, WISCONSIN, ASSIGNOR TO PAPER PATENTS COMPANY, OF NEENAH, WISCONSIN, A CORPORATION OF WISCONSIN

DESIGN FOR A BOX BLANK

Application filed March 18, 1929. Serial No. 30,514. Term of patent 14 years.

To all whom it may concern:

Be it known that I, OSCAR T. THOMPSON, a citizen of the United States, residing in Neenah, county of Winnebago, and State of Wisconsin, have invented a new, original, and ornamental Design for a Box Blank, of which the following is a specification, reference being had to the accompanying drawing, forming a part thereof.

The figure is a plan of a box blank embodying my new design.

The shading on the drawing indicates different tones, shades or colors in the respective zones and not any certain color or colors.

I claim:

The ornamental design for a box blank substantially as shown and described.

OSCAR T. THOMPSON.
